UNITED STATES PATENT OFFICE

HARRY F. LEWIS, OF HAMDEN, CONNECTICUT, ASSIGNOR, BY MESNE ASSIGNMENTS, TO THE GOODYEAR'S INDIA RUBBER GLOVE MANUFACTURING COMPANY, OF NAUGATUCK, CONNECTICUT, A CORPORATION OF CONNECTICUT

CEMENTING MACHINE

Application filed November 23, 1927. Serial No. 235,359.

The invention relates to a device for applying fluid coating composition to an article. More particularly it relates to an improved device for applying cement to sheet material.

5 Machines customarily used for applying cement to the surface of an article of sheet material such as an insole for shoes, do not coat the entire surface of the article when the article contains shallow recesses in its 10 surface. Also in the manipulation of cementing machines customarily used, the cement applied to the article has become im- pregnated with numerous air bubbles. 15 Previously known cementing machines have not applied the cement uniformly over the entire area of the article; nor have the machines been provided with means for positively loosening the entire surface of the 20 treated article from the feed roll. In machines in which the coating roll is adapted to apply the cement to the upper surface of the article, the means for feeding the cement to the roll in the proper amounts have been 25 relatively complicated and inefficient.

It is an object of this invention to provide a device for coating articles with cement uniformly and throughout their entire extent. It is a further object of this invention to provide 30 an improved device for applying cement while maintaining it free from air bubbles. Still another object is to provide a positive means for loosening the entire surface of the cemented article from the feed roll.

35 Other objects will be apparent from the specification and from the accompanying drawings, in which latter:

Fig. 1 is a side elevation of the machine with parts broken away;

40 Fig. 2 is a transverse section through a portion of the machine;

Fig. 3 is a top plan view of the machine;

Fig. 4 is an end elevation of the machine with parts broken away;

45 Fig. 5 is a detailed perspective view greatly enlarged of the coating roll; and

Fig. 6 is a detailed perspective view greatly enlarged of the feed roll.

In its general aspects, the device comprises 50 a feed roll having a knurled surface which is

adapted to feed an insole across its face. A coating roll is positioned in spaced relation to the feed roll and is so rotated that the surface thereof adjoining the feed roll travels in the opposite direction to the feed roll, thereby effecting a wiping action upon the passing insole and applying cement thereto. The cement is carried in recesses in the coating roll and is applied to the coating roll by means of a reservoir which is supported upon 55 the coating roll in liquid tight engagement therewith. Suitable conveyors conduct the insoles to and from the feed roll.

Referring particularly to the drawings, in its preferred embodiment the device comprises a base 1 carrying bearing housings 2 which support rotatable shaft 3 upon which is rigidly mounted the feed roll 4. The feed roll 4 is driven in rotation by means of a sprocket 5 which is rotatably carried upon the shaft 3. The feed roll functions as a support and as a feeding means for the article to be cemented. The hub of the sprocket abuts against a clutch ring 6 which is rigidly mounted upon the shaft 3. A clutch spool 7 is loosely mounted upon the shaft 3 carries rigidly a clutch pin 8 which is adapted to pass loosely through an opening in the clutch ring 6 and to have sliding engagement with one or more recesses 9 in the hub of the sprocket 5. The clutch spool 7 can be adjusted longitudinally upon the shaft 3 to cause the clutch pin 8 to engage with or be disengaged from the hub of the sprocket 5 by means of a lever 10, one end of which engages in a groove in 75 the periphery of the clutch spool 7.

A coating roll 11 is supported in spaced relation to the feed roll 4, being mounted rigidly upon a shaft 12, which latter is supported in bearing brackets 13 which are pivotally supported upon the bearing housings 2 by means of pintle 14. Adjustment of the space between the feed roll 4 and coating roll 11 is effected by means of an adjusting screw 15, which has threaded engagement with one of the bearing brackets 13 and which is adapted to abut against a screw 16 secured in a boss projecting from the bearing housing 2. A lock nut is carried by the adjusting screw for locking the adjustment. By the pivotal 90 95 100

- mounting of the brackets 13, the space between the coating roll and feed roll can be varied when any scrap stock or other foreign substance accidentally passes through the rolls.
- 5 The coating roll is driven in rotation as follows: The shaft 3 carries rigidly a gear 18 which is adapted to engage and drive a gear 19 which in turn engages and drives a gear 20 which is rigidly mounted upon the shaft 12. It will be noted that the adjoining faces of the two rolls pass each other in opposite directions.
- 10 The feed roll or article feeding means is provided upon its surface with a plurality of sharp diamond shaped projections or male members 21 which are so shaped that they are adapted to secure a firm purchase upon the insole or other article with which they engage. The feed roll is provided also with a plurality of annular shallow smooth recesses in its surface which are adapted to be engaged by the projecting teeth of a stripper plate 22 which is so positioned that its teeth extend into the recesses at a location adjoining the upper surface of the roll so as to function to separate the insole from the feed roll and direct the same upon a conveyor to be later described. It will be understood that other shapes can be given the projections 21 so long as they provide a surface which will grip the insole or other article and cause a feed of the article across the surface of the feed roll.
- 15 The coating roll is provided with a plurality of diamond shaped recesses 23 in its surface which are separated by the ribs 24 which constitute the smooth cylindrical outline of the cylinder. The recesses 23 function as pockets to receive the cement applied to the roll and they can be varied in shape so long as they accomplish this purpose. The outer margins of the coating roll form a smooth and even cylindrical bearing 25 for a purpose to be later described.
- 20 45 Cement is applied to the coating roll by means of a reservoir 30 which rests upon and is supported by the coating roll. The lower portion of the reservoir is of generally semi-cylindrical shape. The end walls of the lower portion rest upon the smooth bearing 25 of the coating roll sufficiently tightly to prevent leakage of cement. The side wall 31 of the lower portion of the reservoir 30 rests against the ribs 24 of the coating roll sufficiently tightly and is of sufficient thickness to prevent leakage of cement yet permitting of rotation of the coating roll. A packing member 32 cooperates with the edge 31 to render the joint at this edge liquid tight.
- 25 60 A side wall 33 of the lower portion of the reservoir extends across the face of the coating roll spaced therefrom sufficiently to enable cement which may flow to the outer surface of the ribs 24 of the coating roll during use to be carried past the same. The interior of the lower portion of the reservoir 30 is provided with a cavity 34 which permits of application of the cement to the downwardly passing surface of the coating roll. The cavity is bounded at one end by the web 35 which projects from the reservoir 30 and is positioned to extend across the coating roll in cement tight relation thereto at approximately the top of the roll. The web 35 prevents flow of the cement from cavity 34 down the rear side of the coating roll. Excess cement adhering to the ribs 24 of the coating roll during the operation of applying cement to an insole, is conducted into the recess 36 and becomes banked against web 35 which directs the cement into the recesses of the coating roll so that it can be conducted to the recess 34 of the cement reservoir. A passage way 37 effects communication of the cavity 34 with the reservoir proper. The reservoir is pressed against the surface of the coating roll by means of spring pressed lock pins 38. This holding means provides for the easy removal of the reservoir from the coating roll for cleaning and other purposes. Cement is applied to the reservoir from a receptacle 42 through a conduit 43 and the flow of cement is regulated by means of a valve 44.
- 30 35 40 45 50 55 60 65 70 75 80 85 90 95 100 105 110 115 120 125 130 A work table 46 is supported adjacent the entry side of the rolls and is adapted to carry a supply of insoles to be cemented. A conveyor 47 is supported at one end upon a roll 48 which is rigidly mounted upon a shaft 49 which also rigidly carries a gear 50 which is driven by a gear 51 which latter engages and is driven by the gear 18. A conveyor 52 is positioned upon the opposite side of the rolls for receiving and removing the cemented insoles. The conveyor is supported at one end upon a roll 53 which has rigid connection with a gear 54 which engages and is driven by the gear 19. The conveyor 52 is provided with a plurality of transversely extending U-shaped edged supports 55 which are adapted to receive and support the cemented article upon its edges, thus providing a minimum of supporting surface for the articles.
- 35 40 45 50 55 60 65 70 75 80 85 90 95 100 105 110 115 120 125 130 In the operation of the device, cement is applied from the reservoir 30 to the coating roll 11, filling the recesses in the roll. The coating roll and feed roll are driven in rotation and an insole is placed in position upon the conveyor 47 which is driven to feed the insole to the feed roll. The feed roll engages and positively carries the insole across its surface, thereby bringing the insole into position to be lightly engaged and brushed by the adjoining surface of the coating roll which is moving in the opposite direction. The cement which has a tendency to pass out of the recesses of the coating roll upon the ribs 24, is consequently pressed and rubbed across the surface of the insole, thoroughly coating the entire surface of the insole with cement.

a uniform thickness of cement which is free from air bubbles. The insole engages the stripper plate 22 and is forced thereby from the feed roll and directed toward the conveyor 52 which receives the insole upon the edges of its supports 55 and conducts the same away from the rolls.

While the machine has been particularly described for use in applying cement to insoles, it will be understood that it is equally applicable for applying other liquids. It is also contemplated to use the machine for coating any sheet material with a liquid.

Having thus described my invention what I claim and desire to protect by Letters Patent is:

1. A cementing machine comprising a knurled feed roll, a recessed coating roll, means for applying cement to the recesses of the coating roll, means for actuating the feed roll to conduct an article across the face of the coating roll, and means for actuating the coating roll whereby its face passes in an opposite direction to the adjoining face of the feed roll.

2. A cementing machine comprising a support for an article, a coating roll adapted to cooperate therewith to engage the article, a receptacle adapted to contain liquid cement supported by the coating roll and having communication therewith whereby the cement is applied to the roll, and means for actuating the roll whereby the article is coated with cement.

3. A cementing machine comprising article feeding means, a coating roll adapted to cooperate therewith to engage the article, means for actuating the roll and feeding means, and a receptacle adapted to contain liquid cement supported by the coating roll and having communication therewith upon the side thereof which is moving toward the feeding means.

4. A cementing machine comprising a support adapted to carry an article, a recessed coating roll adapted to cooperate therewith to engage the article, a receptacle adapted to contain cement supported by the coating roll and having communication therewith whereby the recesses are filled with cement, means for actuating the roll whereby cement is applied to the article, and means for engaging excess cement which flows out of the recesses during rotating of the roll.

5. A cementing machine comprising a feed roll having a plurality of annular recesses, a coating roll adapted to cooperate with the feed roll to engage an article, means for applying cement to the coating roll, means for actuating the rolls whereby the article is passed between the rolls and is coated with cement, and stripping means having ribs adapted to engage the annular recesses of the feed roll to positively remove the moving article from the feed roll.

6. A cementing machine comprising a feed roll, a coating roll adapted to cooperate with the feed roll to engage an article, means for applying cement to the coating roll, means for actuating the rolls whereby the article is passed between the rolls and is coated with cement, means for stripping the article from the feed roll, a conveyor juxtaposed to and cooperating with the stripping means and having laterally extending edged supports to receive the cemented article, and means for actuating the conveyor.

Signed at New Haven, county of New Haven, State of Connecticut, this 15th day of November, 1927.
